UNITED STATES PATENT OFFICE.

FRANK M. HARDESTY, OF CAMBRIDGE, OHIO, ASSIGNOR OF ONE-HALF TO CHARLES F. LOWRY, OF CAMBRIDGE, OHIO.

DEVICE FOR HANDLING A PLURALITY OF TRAIN-ORDERS AND MESSAGES.

1,184,448.

Specification of Letters Patent.

Patented May 23, 1916.

Application filed January 7, 1916. Serial No. 70,804.

To all whom it may concern:

Be it known that I, FRANK M. HARDESTY, a citizen of the United States, residing at Cambridge, in the county of Guernsey and State of Ohio, have invented certain new and useful Improvements in Devices for Handling a Plurality of Train-Orders and Messages, of which the following is a specification.

10 My invention relates to brackets for holding train orders for delivery to the crew of passing trains.

The object of my invention is to produce a bracket on which a plurality of manuscript orders may be separately carried and separately held in position, to be detached by members of the crew of a passing train.

A further object thereof is to produce a bracket of said character, in which one copy 20 may be held adjacent to a railroad track, the detachment of which actuates the mechanism in my device to immediately position the other copy for detachment by another member of the crew, and a still further object of my invention is to produce a more 25 simple, cheap and efficient delivery device of the character described than has heretofore been attained.

To these ends, my invention includes the 30 combination and arrangement of component parts to be hereinafter described and more particularly pointed out in the claim.

In the accompanying drawings in which like reference characters indicate similar parts, Figure 1 is a perspective view of my device; Fig. 2 is a side elevation, showing one of the pairs of arms in operative position; Fig. 3 is a similar view, showing the second pair in operative position; Fig. 4 is 40 a ground plan view, showing my device in the position shown in Fig. 2, and Fig. 5 is a similar view, showing the position assumed in Fig. 3.

My invention includes, generally, a vertical mast rigidly carried in a suitable foundation, a gear for imparting a quarter turn to said mast, a weight for actuating said gear, a pair of laterally projecting, pivoted arms and an endless cord for holding same 50 in extended position, a pair of similar arms carried on the mast at an angle of 90° to the first-mentioned arms, each of which pairs of arms are adapted to hold a message in position to be conveniently detached by 55 the crew of a passing train, and means con-

nected with the first-mentioned pair of arms for releasing the weight-actuated gear for rotating said mast.

Referring more particularly to the drawings, the numeral 1 designates a mast adapted to be vertically mounted in a plate 2 adjacent to the side of a railroad track, and said mast is held in vertical position by the housing 3, through the top of which it projects. Said housing is suitably secured upon the platform or foundation 4.

Adjacent to the lower end of the mast 1 and within the housing 3 is rigidly secured the bevel gear 5, adapted to mesh with the bevel gear 6 secured on one end of the shaft 7, which is journaled in the bearing 8 in the wall of the housing 3 farthest removed from the railroad track. On the opposite end of the shaft 7 is secured the arm 9, upon the outer end of which is carried the weight 10, and said arm and weight are adapted to be held in raised position when the parallel arms 11 and 11' are held in position at right angles to the railroad track and to be released from such elevation by the collapse of said arms upon the removal of the message carried thereon, whereby the gear 5 is turned the fourth of a circle to position the other pair of arms 12 and 12' at right angles with the track, as hereinafter described.

The arms 11 and 11' are pivotally mounted on the mast 1 at *a* and *b* respectively and the arm 11 is provided with an extension 11^a extending rearwardly, upon the end of which is attached a chain 13 at its upper end, while its lower end is attached to the arm 9 intermediate of its ends. The arm 11' projects slightly rearwardly at 11^b to engage the lug or pin 14 on its lower face. Said arms 11 and 11' are held in horizontal parallel position by the endless cord 24, which passes over the outer ends of each of the arms at *c* and *d* and is engaged by the clips 15 and 16 carried on the mast 1 adjacent to the pivots *a* and *b* of said arms, and an envelop 17 is attached to said cord in convenient position for detachment by the crew of a passing train. The outer ends of the arms 11 and 11' are notched vertically to retain the cord in position.

When the arms 11 and 11' are in the extended position shown in Figs. 1 and 2, the weight-bearing arm 9 is held in raised position by the extension 11^a of the arm 11, and when the envelop 17 is detached and together 110

with the cord 24 which normally holds the arms 11 and 11' in horizontal position the outer end of the arm 11 is raised by the weight of the arm 9 and its weight 10 to permit the arm 9 to fall and thus impart a quarter turn to the gear 6, thereby turning the gear 5 and mast 1 to bring the arms 12 and 12' into the position formerly occupied by the arms 11 and 11'. The arms 12 and 12' are held in horizontal position by the cord 23 which passes over the outer end of each of the arms and is engaged by the clips 17 and 18 carried on the mast 1, and the envelop 19 is carried on the cord 23 in convenient reach of another member of the crew of a passing train. Said arms 12 and 12' are pivoted adjacent to their inner ends on the mast 1 and are coupled together by the bent rod or pitman 20, which is pivoted at its lower end on the inward extension 21 of the arm 12' and at its upper end to the outwardly extending portion of the arm 12, whereby when the cord 23 is removed and the arm 12' allowed to drop, its weight will force the arm 12 upwardly and thus remove the danger to passing trains of a laterally projecting arm.

From the foregoing description and by reference to the accompanying drawings, it will be appreciated that my device provides for the delivery of two copies of train messages to a passing train, the removal of the first of which immediately positions the second for removal by another member of the crew, and it will be further apparent that the automatic action of my device returns each one of the laterally projecting arms to

a vertical position when the messages have been detached.

Having thus described my invention, what I claim as new and desire to be secured by Letters Patent, is—

A device of the character described, comprising a vertical rotatable mast and means for rotating said mast, a pair of horizontally pivoted arms carried on said mast, one of which is provided with a rearwardly extending projection, a pair of clips carried on the mast adjacent to the pivotal points of the arms, an endless order-holding cord adapted to engage the ends of said arms and said clips to hold the arms in horizontal position, a flexible connection between the rearwardly extending projection on one of the arms and the means for rotating the mast, by which said means are actuated upon the detachment of said cord, a second pair of horizontally pivoted arms, a plurality of spring clips adjacent to the pivotal points thereof, an order-holding cord connected with the ends of said arms and said clips to hold the arms in horizontal position, and a rod connecting said second pair of arms adapted to raise the upper arm into vertical position upon the detachment of said order-holding cord and the consequent dropping of the lower of said arms, substantially as described.

In testimony whereof I affix my signature in presence of two witnesses.

FRANK M. HARDESTY.
